UNITED STATES PATENT OFFICE

GLENN MUFFLY, OF DETROIT, MICHIGAN, ASSIGNOR TO COPELAND PRODUCTS, INC.,
OF DETROIT, MICHIGAN, A CORPORATION OF MICHIGAN

REFRIGERATING APPARATUS

Application filed March 3, 1927. Serial No. 172,273.

In the provision of refrigerant tanks which are to supply refrigerant to expansion chambers of refrigerating systems considerable difficulty has heretofore been encountered in 5 adjusting the liquid level of the refrigerant in the expansion chamber. It has been customary to provide float controlled valves in the refrigerant tanks and in order to adjust the position of same, it has been necessary 10 to either provide the adjustment on the inside of the tank, necessitating disassembly of the tank in order to make the adjustment, or to extend the adjustment through a packed gland to the outside of the tank.

15 It is one of the primary objects of my invention to provide for an adjustment of the fluid level without either of these contingencies being present. Specifically, my invention encompasses the positioning of the refrigerant tank in such a manner that it may be raised or lowered with respect to the expansion chamber, and the refrigerant in the chamber thereby easily controlled without any possibility of leakage or necessity for 20 disassembly of the parts in order to secure the adjustment.

With the above and other objects in view, my invention consists in the arrangement, combination and construction of the various 25 parts of my improved device as described in the specification, claimed in my claims and shown in the accompanying drawings, in which:

Fig. 1 is a transverse sectional view of an 30 expansion chamber and refrigerant tank embodying my invention.

Fig. 2 is a sectional view taken longitudinally of the tank.

Fig. 3 is a detail view taken on line 3-3 40 of Fig. 1.

I have shown an expansion chamber 5 of the conventional sheet metal type, embodying superposed sheets of metal 6 and 7, the edges of which are suitably joined and sealed as 45 at 8 and the intermediate portions of which are spot-welded together as at 9 to provide refrigerant courses between the sheets.

Secured to the freezer and particularly on the sheet 6 is an angle bracket 29 having an 50 elongated slot 10 therein. Extending

through the slot 10 is a bolt 11 which also extends through an aperture in the abutting face of the angle bracket 12 which is provided on a refrigerant container or tank 13. A lock washer 14 and nut 15 serve to secure the brackets 29 and 12 together, it being readily apparent that by loosening the nut 15 the tank 13 may be vertically adjusted by reason of the movement of the bolt 11 in the slot 10 of the bracket 29.

Refrigerant from a suitable source of supply is fed to the tank 13 through a pipe 16, passage 17 and needle valve 18, the latter being controlled by the float 19 secured on the rod 20 which is pivoted to the tank as at 21.

A passage 22 extends from adjacent the bottom of the tank 13 to the bottom of a portion of the expansion chamber 5 and a similar passage 23 extends from adjacent the top of the tank 13 to the top of a portion of the expansion chamber 5. Thus refrigerant may pass from the tank 13 to the chamber 5 until the level in the two is equal, as shown in Fig. 1. If it is desired to lower 70 the level of the refrigerant in the chamber 5, it is necessary only to lower the tank 13 by loosening the nut 15 and lowering the bracket 12 in its connection with the bracket 29. Obviously, the level in the chamber 5 75 may be raised by elevating the tank in the same manner.

It will be obvious that the dual passages 22 and 23 serve to equalize the levels between the expansion chamber 5 and tank 13 80 and that these passages should consist of flexible tubing or other suitable material which will permit of bending when the tank and chamber are vertically adjusted relative to each other.

It will be obvious that my invention may be served by tilting the assembly of expansion chamber and refrigerant tank, so that I desire it to be understood that my invention encompasses the vertical adjustment of the two elements with respect to each other irrespective of how the adjustment is accomplished.

It will be obvious that various changes may be made in the arrangement, combina- 100

tion and construction of the various parts of my improved device without departing from the spirit of my invention, and it is my intention to cover by my claims such changes as may be reasonably included within the scope thereof.

What I claim is:

1. In combination, a refrigerant container and an expansion chamber, a passage connecting the two, a bolt extending through apertures in co-operating brackets on the chamber and container, at least one of said apertures being elongated, and means for securing the bolt in the apertures to hold the chamber and container in adjustable assembly.
10
2. In combination, a refrigerant container and an expansion chamber, a passage connecting the two, a bracket on the container and a bracket on the chamber, each having an aperture therein, at least one of the apertures being elongated, and a bolt extended through
20 the apertures and securing the container and chamber in adjustable assembly.
